ATTORNEY

UNITED STATES PATENT OFFICE

160,773

PLAQUE

Dino J. Cristofoletti, New York, N. Y.

Application October 28, 1949, Serial No. 5,749

Term of patent 14 years

(Cl. D29—23)

To all whom it may concern:

Be it known that I, Dino J. Cristofoletti, a citizen of the United States, residing at New York city, in the county of New York and State of New York, have invented a new, original, and ornamental Design for a Plaque, of which the following is a specification, reference being had to the accompanying drawing, forming part thereof, in which

Fig. 1 is a front view of a plaque, showing my new design; and

Fig. 2 is a cross sectional view taken along the line 2—2 of Fig. 1.

I claim:

The ornamental design for a Plaque, as shown.
DINO J. CRISTOFOLETTI.
